UNITED STATES PATENT OFFICE

CLIFFORD V. MILLIGAN, OF HOUSTON, TEXAS

FLATWORK IRONER

Application filed February 17, 1930. Serial No. 429,000.

This invention relates to new and useful improvements in a flat work ironer.

One object of the invention is to provide a machine of the character described, especially designed for the purpose of flat work, such as bed sheets, spreads, towels and the like in the process of laundering the same.

Another object of the invention is to provide a machine of the character described and for the purpose stated that is of such construction that it may be automatically operated, and that the operators thereof will not be liable to be injured thereby.

With the above and other objects in view this invention has particular relation to certain novel features of construction, operation, and arrangement of parts, an example of which is given in this specification and illustrated in the accompanying drawings, wherein:—

Figure 1 shows a plan view of the machine, with the feed apron removed.

Figure 2 shows a side view of the machine.

Figure 3 shows a cross sectional view taken on the line 3—3 of Figure 1, and

Figure 4 shows a transverse vertical sectional view taken on the line 4—4 of figure 1.

Referring now more particularly to the drawings, wherein like numerals of reference designate similar parts in each of the figures, the numeral 1 designates the bed of the machine whose upper surface is flat and smooth and has a yieldable pad 2 thereon. The bed is preferably hollow, providing a steam heating chamber 3 therein. The heating fluid may be supplied to said chamber through one of the pipes 4 and relieved therefrom through the other pipe 4. The bed is supported on suitable legs, as 5.

Above the bed 2 there is a flat iron 6 also hollow, providing the steam heating chamber 7. Heating fluid may be delivered to said chamber 7 through one of the pipes 8 and relieved therefrom through the other pipe 8. The underside of the flat iron 6 is flat and smooth and confronts, and coincides in position with, the pad 2.

The side margins of the flat iron have the outstanding lugs 9, having the vertical bear-

ings 10 therethrough and upstanding from the side margins of the bed 1 are the guides 11 which extend through said bearings. Surrounding said guides and interposed between the bed 1 and the lugs 9 are the strong coil springs 12, which normally hold the flat iron spaced above the bed pad.

At the forward end of the machine there is a frame consisting of suitable supporting legs 13 and side and end bars 14 and 15.

This frame supports the upper transverse rollers 16 and the lower rollers 17 and at the opposite end of the machine is the upper transverse roller 18, and the legs 5 support the lower transverse rollers 19, one, at least, of which is vertically movable. An endless apron 20 is supported on and travels around said rollers as shown in Figure 2.

The shafts of the rollers 16, 18 are extended, at one end, and have the sprockets 21 fixed thereon, and one of said shafts may be driven, in any suitable manner as by a motor 22 which drives the belt 23, which in turn operates over a pulley 24 fixed on said driven shaft. A sprocket chain 25 operates over the sprockets 21 and through this driving mechanism the feed apron 20 may be driven.

Mounted in bearings 26, on opposite sides of the bed 1 are the crank shafts 27, 27 whose wrists 28 are connected to the lugs 9 by means of the connecting rods 29.

At the ends of the bed 1 there are the fluid pressure cylinders 30, whose inner ends are pivoted to the corresponding brackets 31. Each cylinder has the usual piston therein and the outwardly extending piston rod 32 whose free end is pivotally connected to the free end of a depending arm 33, fixed to the adjacent end of the corresponding crank shaft 27. The cylinders 30 have the inlet lines 34 for the admission of pressure fluid into the cylinders behind the pistons. When such fluid is thus admitted the pistons are forced outwardly and the crank shafts are partially rotated to pull the flat iron 6 downwardly onto the pad 2. When the pressure is released from said cylinders the springs 12 will elevate said flat iron 6.

In use the flat work to be ironed is fed onto the outer, or forward, end of the apron 20,

manually, a piece at a time and is carried by said apron onto the pad 2. The apron 20 is then stopped and pressure fluid is delivered into the cylinders 30 and the flat iron 6 is forced down onto the flat work, on said pad. Meanwhile hot steam is circulated through the chambers 3, 7. When the laundry on the pad is thus ironed the pressure is released from the cylinders 30 and the flat iron is elevated through the springs, 12. The apron 20 is then started and the ironed laundry will be carried from the machine to be folded and another piece will be simultaneously delivered to the pad 2.

15 In a practical embodiment of the machine provision will be made for automatically stopping and starting the apron 20 as well as for automatically applying the pressure fluid to, and releasing the same from, the cylinders 30 and these movements will be so synchronized that the apron will stop and start at regular intervals and the pressure fluid will be applied when the apron stops and released when the apron is started.

20 25 The drawings and description disclose what is now considered to be a preferred form of the invention by way of illustration only while the broad principle of the invention will be defined by the appended claim.

30 What I claim is:—

A machine of the character described including a supporting bed, an endless feed apron movable over the bed, a flat iron above and adapted to cooperate with said bed, means normally holding the flat iron spaced above the bed, crank shafts, connecting rods connecting said shafts to the flat iron, on each side, means operable by fluid under pressure for rocking said shafts whereby the flat iron may be moved into cooperating relation with said bed.

In testimony whereof I have signed my name to this specification.

CLIFFORD V. MILLIGAN.
